UNITED STATES PATENT OFFICE.

CURT STILLE, OF FRIEDENAU, NEAR BERLIN, GERMANY.

ELECTRIC SECURITY DEVICE.

1,159,128.

Specification of Letters Patent.

Patented Nov. 2, 1915.

Application filed July 18, 1911. Serial No. 639,215.

To all whom it may concern:

Be it known that I, CURT STILLE, of Friedenau, a subject of the King of Prussia, and whose post-office address is 29 Südwest 5 Corso, Friedenau, near Berlin, Kingdom of Prussia, German Empire, have invented a new and useful Electric Security Device; and I do hereby declare that the following is a full, clear, and exact description of my invention, which will enable others skilled in the art to which it appertains to make and use the same.

For many purposes, for instance for military purposes, when it is desired to fire mines, relays are used which are operated by impulses from a distance in order to close a circuit for firing the mine. It is particularly advantageous that only authorized persons familiar with the apparatus should 20 be able to operate the device. This requirement is fulfilled by the present invention. The release takes place only when a given number of wave impulses (acoustic, optical or electric) are given, and only when the 25 impulses are given within a time interval. For generating the wave impulses acoustic, optical, or electric devices can be used, as for instance a diaphragm, which responds either to a sound or to a tuned note by 30 resonance. Light waves or impulses can act on selenium cells, while electrical action can be obtained by the use of Hertzian waves, etc.

A device according to this invention is 35 illustrated in the accompanying drawing, wherein the single electromagnets and switches which are united in the apparatus are shown diagrammatically with the electric connections; the switch belonging to 40 the time switch being shown in development.

The switch A is an adjustable time switch of the usual kind, that is to say, on switching it in, a small clockwork is wound up 45 which runs down in a given time interval, which can be, however, adjusted as desired. The winding device of the clock work (not shown in the drawing) is marked by the letter a. The time switch is provided with a 50 reversing device on the rotating spindle of the clockwork, which is shown in development. This switching device can be made in the shape of a drum or disk. It has a series of contact parts b_1, b_2, b_3, b_4 , arranged on 55 the drum, as well as corresponding sliding parts $c_1, c'_1, c_2, c'_2, c_3, c'_3, c_4, c'_4$, indicated by

small circles. When the drum rotates it moves in the direction of the arrow, and different circuits are closed by the engagement of the contacts with the contact pieces. 60

The step switch B is an electromagnet, which at each impulse rotates by means of a pawl d and a ratchet wheel e, a contact disk f to an extent corresponding to one tooth of the ratchet wheel. In this way, the 65 contact piece g, which is on the disk f finally comes into contact with the two contacts h, h_1 . This step switch is further provided with a return device, that is to say, with a device for bringing it back to its 70 initial position. The device chiefly consists of a small electromagnet i which disengages a pawl k from the ratchet wheel e, so that the latter, together with the contact disk will return to its initial position under the action of a spring, not shown in the drawing. 75

The synchronizing switch C is merely an electromagnet with a contact breaker l_1, l_2 which it has to close, while the working switch D is an electromagnet which at each 80 impulse performs some work, for instance brings a contact disk into and out of contact with the ignition circuit of the mine (assuming still the example selected).

If the circuits are followed in detail, it 85 will be obvious that this apparatus fulfills completely the conditions referred to. The first impulse closes the contact E, that is to say, completes a circuit passing through the battery m, the winding of the electromagnet 90 A, the contact c_1 , the contact plate b_1 , and the contact c'_1 , back to the contact E. A second circuit is formed through the battery m, the winding of the electromagnet B, through the contact c'_2 , contact plate b_2 , contact 95 c'_2 , back to E. The other circuits are on the contrary open. The disk or drum secured to the clockwork, occupies during that time the position $x-x$. This impulse brings about two results; on the one hand, it starts the 100 time switch A, and then the step switch B. The time switch then continues to run, the drum moving to the position where the contacts $b_1 \dots c'_4$ are on the line Y-Y, that is to say, the second impulse does not affect 105 the time switch, but passes through the step switch B, so that the ratchet wheel e and with it the contact disk, are moved to the extent of one tooth by each impulse. Finally, the contacts $b_1 \dots c'_4$ come into the position 110 on line Z-Z, and at that moment, the contact g is in contact with the contacts h, h_1

providing the predetermined impulses have been received. At that moment, however, the circuit of the electromagnet of the switch C is closed, through the contact b_4 , a current flowing from the battery o through c'_4 , b_4 , c_4 , contact h , contact g , contact h_1 , the winding of the electromagnet of C and back to the battery o . As soon as the electromagnet C is energized, it closes, in its turn, the working switch D, that is to say, a circuit is closed through the battery p , the contacts l_1 , l_2 and the winding of the electromagnet D. The armature of the electromagnet D can then perform the work allotted to it. The switch apparatus, by means of the contact piece b_3 , then releases the step device, the circuit of the battery n being closed over the winding of the electromagnet i . The energized electromagnet attracts its armature and thus disengages the pawl h from the ratchet wheel e , so that the latter is returned by its spring to its original position.

It will however be obvious that if the impulses are not given in correct manner, the switch D will not become operative. If, for instance, the impulses are given within a time interval which is longer than that prescribed, the time switch, on its time interval expiring will release, by means of its contact device, b_3 , the return device of the step switch B, so that the latter will return to its initial position, that is to say, will not occupy at the last impulse the contact position. Thus the switch C, and consequently the switch D are prevented from responding. If on the contrary, the impulses are given in a time interval shorter than that prescribed and the impulses are continued, no exciting takes place in the switch C, as contact g will have passed beyond contacts h , h_1 when contact b_4 reaches contacts c_4 , c'_4 and the switch D will not therefore respond. The time switch, on the contrary, returns after the expiration of the time interval, to its original position.

When the time interval of the time switch is altered by adjustment, and the contact disk f with the contact g is replaced by another one, the conditions will be altered, so that a large number of combinations for producing the release, will be obtained. If moreover the diaphragm in case of the use of acoustic waves, is arranged in such manner that it responds only to a given note, this number will be correspondingly increased. Finally, some applications of the invention may be mentioned.

For military purposes, the firing of mines has already been referred to. Further, the firing and sinking of torpedoes, the giving of certain signals may be cited, in which case the release can be effected more particularly by projectors or by waves. Such a case would be for instance that of an elec-

tric railway which is started by ringing a bell or by whistling.

Having fully described my invention, what I desire to claim, and secure by Letters Patent of the United States, is:—

1. A security device comprising electric circuits, containing three electromagnetic elements, the first a time switch operated by electric impulses to change said circuits, a step by step mechanism operated by electric impulses in the circuit closed by the time switch, said step by step mechanism being provided with a contact device able to close a circuit simultaneously with the contact device of the time switch and having a means for resetting the said mechanism, the resetting device arranged in circuit controlled by the time switch, substantially as set forth. 70 75 80

2. In a security device the combination with a relay adapted to be actuated by the simultaneous action of two contact elements in its circuit, of a step by step mechanism adapted to close the first of the two contact elements after having proceeded with a certain number of steps, a time switch provided with contact elements adapted to close the circuit after the elapsing of a certain period and an impulse receiving apparatus provided with a contact device for closing the circuit of the time switch. 85 90 95

3. In a security device the combination with a relay adapted to be actuated by the simultaneous action of two contacts closing or opening the circuit of the relay, of a step by step mechanism and electromagnet 100 for it, a contact apparatus adapted to close the first contact of the relay circuit after a certain number of steps, a time switch provided with a contact device rotated by the time switch and adapted to close the second contact of the relay circuit after being rotated a certain angle in a certain period and an impulse receiving apparatus provided with an electromagnet and a contact device for closing the circuit of the said electromagnet, substantially as set forth. 105 110 115

4. In a security device the combination with a relay adapted to be actuated by the simultaneous action of two contact elements in its circuit, of a step by step mechanism adapted to close the first of the two contact elements after having proceeded a certain number of steps, a releasing mechanism for said step by step mechanism, a time switch provided with contact elements adapted to close the circuit after the elapsing of a certain period and an impulse receiving apparatus provided with a contact device for closing the circuit of the time switch. 120 125

5. In a security device the combination with a relay adapted to be actuated by the simultaneous action of two contact elements in its circuit, of a step by step mechanism adapted to close the first of the two contact elements after having proceeded a certain 130

number of steps, means for turning back said step by step mechanism after a certain number of steps, a time switch provided with contact elements adapted to close the circuit after the elapsing of a certain period and an impulse receiving apparatus provided with a contact device for closing the circuit of the time switch.

6. In a security device the combination 10 with a relay adapted to be actuated by the simultaneous action of two contacts closing or opening the circuit of the relay, of a step by step mechanism and an electromagnet for it, a contact apparatus adapted to close the first contact of the relay circuit after a certain number of steps, a releasing mechanism for said step by step mechanism, a time switch provided with a contact device rotated by the time switch and adapted to 15 close the second contact of the relay circuit after being rotated a certain angle in a certain period and an impulse receiving apparatus provided with an electromagnet and a contact device for closing the circuit of 20 the said electromagnet, substantially as set forth.

25

7. In a security device the combination with a relay adapted to be actuated by the simultaneous action of two contacts closing or opening the circuit of the relay, of a step 30 by step mechanism and an electromagnet for it, a contact apparatus adapted to close the first contact of the relay circuit after a certain number of steps, means for turning back said step by step mechanism after 35 a certain number of steps, a time switch provided with a contact device rotated by the time switch and adapted to close the second contact of the relay circuit after being rotated a certain angle in a certain period and an impulse receiving apparatus provided with an electromagnet and a contact device for closing the circuit of the said electromagnet, substantially as set forth.

In testimony whereof I have hereunto set 40 my hand in presence of two subscribing witnesses.
